COMBINED TELEVISION ANTENNA AND LAMP

Cline M. Hodson, 26 Larchmont Road, Buffalo, N.Y.

Filed Nov. 18, 1959, Ser. No. 58,389

Term of patent 3½ years

(Cl. D48—20)

Fig. 1 is a perspective view of a combined television antenna and lamp, with the antenna arms in a fully extended position, showing my new design;

Fig. 2 is a top plan view thereof on an enlarged scale, with the outer ends of the antenna arms broken away for ease of illustration;

Fig. 3 is a fragmentary, front elevational view thereof, with an antenna arm in its fully retracted position; and

Fig. 4 is a top plan view of Fig. 3.

The essential features of my design reside in those portions shown in solid lines.

I claim:

The ornamental design for a combined television antenna and lamp, substantially as shown and described.
